REFRIGERANT CONTAINER

Kurt E. Zeidler, Pittsburgh, Pa., assignor, by
mesne assignments, to Standard Railway Re-
frigerator Company, a corporation of Delaware

Application August 1, 1938, Serial No. 222,383

7 Claims. (Cl. 62—17)

This invention relates to refrigerator cars used to transport perishable commodities at a temperature within a predetermined range. This necessitates use of a cooling means in summer 5 and a heating means in winter.

A refrigerator car comprises insulated walls, roof and floor and, when used in warm weather, a means for cooling the air as it circulates about the car. The cooling means may be fresh water 10 ice, a mixture of ice and salt, a brine solution, or a eutectic ice consisting of frozen brine. Said means may be placed at the ends of the car and separated by bulkheads from the lading compartment or may be suspended immediately below the 15 ceiling.

This invention applies particularly to cars in which there are preferably a plurality of refrigerant containers near the roof and more particularly to cars in which the containers are solid 20 tanks designed to retain a liquid refrigerant, such as brine. Hatches are provided in the roof above the containers for the deposit of refrigerant therein. A drip pan or partition is preferably provided to catch and drain condensation 25 dropping from the tank. A flue is also preferable to communicate between the passage above the partition and the space between the floor and the floor rack.

Refrigerator cars are used for two general purposes. They are used with a heating or cooling 30 means, depending upon the season, to keep the lading at some predetermined temperature and they are used under ventilation when the lading is of a type that emits heat during transit. This 35 heat must be removed to protect the lading from an injuriously high temperature. Cars having foraminous refrigerant containers are relatively easy to ventilate; it is necessary only to remove the covers from the hatches. Cars intended for 40 use in certain types of service, however, have imperforate tanks to retain the liquid brine which is necessary to produce the low temperatures required. Since these tanks must be water tight, they are also air tight, therefore, it is impossible 45 to ventilate the car merely by removing covers from the hatches.

It is an object of this invention to provide means to ventilate a car equipped with brine tanks. It is a further object of the invention to 50 design the ventilating means to insure retention of the brine. If the brine should leak from the container the car would not only be deprived of its refrigerating effect, but the lading would be exposed to damage from brine dripping on 55 it. Another object of the invention is to provide a ventilating means easily accessible for operation. It is a further object to design the operating means to be easily operated and preferably made adjustable to control the amount of ventilating 60 air entering the car.

In the drawings:

Fig. 1 is a vertical transverse section of a refrigerator car equipped with my invention. The left half of the section is on line 1L—1L of Fig. 3 and the right half on line 1R—1R of Fig. 3. 5

Fig. 2 is a fragmentary transverse section showing a hatch cover arranged for ventilation.

Fig. 3 is a vertical longitudinal section on line 3—3 of Fig. 1.

Fig. 4 is a fragmentary longitudinal section 10 showing a ventilating door arranged for ventilation.

Fig. 5 shows a modified construction.

In Fig. 1 the usual parts of a refrigerator car are shown, such as center sill 2; side sills 3; underframe cross members 4; sub-floor 5; floor 6; floor rack 7; side sheathing 8; side lining 9; auxiliary walls 10 providing the flues 11; side plates 12; outer roof sheets 13; running board 14; ceiling 15; hatch frames 16 surrounding the hatches 17; refrigerant tanks 18; drip pans or partitions 19; insulation 20; lading compartment 21; drain pipe 22, and a valve 23 to close the pipe 22. 15 20

The tanks 18 are made from imperforate metallic sheet, preferably welded, and are reinforced by a series of angles 30 surrounding the tank 18 and secured thereto. A series of beams 31 are secured to the tanks 18 and rest upon members 32 which are secured to the side wall structure of the car. Each tank 18 has an opening in the top approximately the size of the hatch 17 and an upstanding flange 33 surrounding the opening and joining with the hatch frame 16. It is important that the tank 18 be joined to the hatch frame 16 to prevent liquid from 35 splashing out of the container during jolting of the car which occurs in service. 30 35

Some of the tanks 18 are provided with an aperture in the bottom thereof. Each aperture has an imperforate web 41 surrounding the aperture with reinforcing members 42 at the top of the web 41 to provide a rigid structure. A door 43 is hinged at 44 to the tank 18 and arranged to close the flue 40 formed by the web 41. 40

The drawings illustrate the flue 40 positioned 45 in a corner of the tank 18. This arrangement would make part of the web 41 coincident with a wall of the tank 18. Since said web and wall would serve no purpose, they are removed to give the construction shown in Figs. 1 and 3. 50

A threaded rod 45 is pivoted at 46 to the under side of the door 43. The door 43 is secured in its horizontal closed position, as shown in Fig. 3, by clamping the two wing-nuts 47—48 against the lower lug 49. A gasket 50 made of rubber, or 55 other pliable material, is secured to the door 43 to provide a water-tight joint when in the position shown in Fig. 3.

Fig. 4 shows the door 43 in the open or ventilating position. It is secured in this position by 60

clamping the wing-nuts 47-48 against the upper lug 51. The amount of the opening may be adjusted by varying the position of the wing-nuts 47-48 on the rod 45.

Fig. 2 shows the method of arranging the hatch 17 for ventilation. An insulated plug 60 is ordinarily provided to prevent heat entering the tank 18 and melting the refrigerant. A cover 61 is also provided to keep dirt and water from accumulating on top of the plug 60. The cover 61 is hinged at 65 at one edge thereof to the roof structure and provided with an adjustable latch 62 to partially elevate the cover 61. Overlapping clips 63-64 are secured to the under side of the cover 61 and the top side of the plug 60. When it is desired to ventilate the car, the cover 61 is raised to the position shown and held by the latch 62; the plug 60 is held clear of the hatch frame 16 by the clips 63-64. When the car is operated under refrigeration, the plug 60 is wedged tightly into the hatch frame 16 and insulates the tank 18.

The partition 19 is provided with a door 70 hinged at 71 to the partition 19. The door 70 is below the door 43 in the tank 18 to provide a path for the ventilating air. A latch 72 is provided to hold the door 70 in the closed position and means is also provided to hold the door in the open position.

The drawings show the ventilating door 43 positioned at one corner of the tank 18. The purpose of this is to prevent moisture from the hatch from entering the lading compartment by way of the aperture 40 in the bottom of the tank. Any other position of said aperture does not materially change the function thereof, and is included in the scope of the invention.

Fig. 5 shows a modified construction designed to eliminate the door 43. The aperture 80 in the bottom 85 of the container is positioned directly below the hatch 17 and the web 81 is arranged to extend to adjacent the hatch plug 60. A pad 82 of rubber or other pliable material is fitted to the bottom of the plug 60 so that the pad 82 closes the flue 83 when the plug 60 closes the hatch. A separate door is not required to close the flue 83. When the car is under refrigeration, both hatch 17 and flue 83 are closed by the plug 60 and when it is desired to ventilate, it is necessary only to remove the plug 60. A door 84 is provided in the partition 19 for ventilating purposes.

When a brine solution is used in the tanks it will be certain of retention to the height of the door 43. The door 43 is arranged to be clamped to the web 41 tightly to provide a watertight connection. However, workmen employed by the railroads are frequently very careless so it must be considered that the door 43 may be unclamped at times and liquid above the door would be lost, therefore, the ventilating door 43 is spaced a distance above the bottom of the container to insure the retention of at least a part of the brine.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car, a roof provided with

a hatch, a refrigerant tank below said hatch and above the lading compartment of the car, said tank having an aperture in the bottom thereof with an upstanding web surrounding said aperture to provide a flue communicating with said lading compartment, and closure means for said flue.

2. In a refrigerator car, a roof provided with a hatch, a refrigerant tank below said hatch and above the lading compartment of the car, said tank having an aperture in the bottom thereof with an upstanding web surrounding said aperture to provide a flue communicating with said lading compartment, closure means for said flue, and means to operate said closure means to vary the area of said flue.

3. In a refrigerator car, a roof provided with a hatch, a refrigerant tank below said hatch and above the lading compartment of the car, said tank having an aperture in the bottom thereof with an upstanding web surrounding said aperture to provide a flue communicating with said lading compartment, closure means for said flue, and means to operate said closure means from within said lading compartment.

4. In a refrigerator car, a roof provided with a hatch, a refrigerant tank below said hatch and above the lading compartment of the car, and a substantially horizontal partition below said tank, said tank having an aperture in the bottom thereof with an upstanding web surrounding said aperture to provide a flue and said partition having an opening below said aperture for communication between said flue and said lading compartment.

5. In a refrigerator car, a roof provided with a hatch, a refrigerant tank below said hatch and above the lading compartment of the car, said tank having an aperture in the bottom thereof with an upstanding web surrounding said aperture to provide a flue communicating with said lading compartment, said flue being underneath said hatch, and a plug adapted to close said hatch and said flue.

6. In a refrigerator car, a roof provided with a hatch, a refrigerant tank below said hatch and above the lading compartment of the car, a substantially horizontal partition below said tank, said tank having an aperture in the bottom thereof with an upstanding web surrounding said aperture to provide a flue, said partition having an opening below said aperture for communication between said flue and said lading compartment, closure means for said flue, means to operate said closure means from within said lading compartment, and means for closing said opening.

7. In a refrigerator car, a roof provided with a hatch and a refrigerant tank below said hatch and above the lading compartment of the car, said tank being substantially closed except for an opening in the top communicating with said hatch, and an aperture in the bottom with an upstanding web surrounding said aperture to provide a flue communicating with said lading compartment thereby providing a path for ventilating air through said hatch and said flue to said lading compartment, said flue being positioned remote from said hatch to prevent entrance of moisture from said hatch to said flue.

KURT E. ZEIDLER.
